Application January 23, 1933, Serial No. 653,016

10 Claims. (Cl. 221—95)

My invention relates to liquid dispensing apparatus, and the objects of my invention are to provide control means whereby a pump or other liquid forcing means is operable either simultaneously with the opening of a valve controlling the flow of liquid through the hose, or other conduit, or is operable subsequently to the opening of such valve, and whereby the pump or other liquid forcing means is maintained in operation simultaneously with the opening of such valve, whereby on the initiation of the dispensing operation, hammering action is avoided, and whereby at or toward the conclusion of the dispensing operation, the pressure on the liquid is maintained until after the closure of the valve, whereby relatively small quantities of liquid may be dispensed under pressure as the end of the dispensing operation approaches; another object is to provide means of the foregoing character wherein the control of the pump or other liquid forcing means is effected from and by the nozzle control valve at the end of the hose.

Another object is to provide mechanism for carrying out the foregoing sequence of operation of the pump and valve whereby said sequence may be carried out by any type of remote control mechanism either electrically, pneumatically, hydraulically or by mechanical means such as a Bowden wire, and the like; to provide a simple type of control means for providing the foregoing sequence, which is mounted in the nozzle for operating the nozzle valve, and also the pump operating mechanism by a simple manual movement; to provide an adantation of my invention whereby the control is effected from a manually operable member disposed at the side of the housing instead of from the nozzle; to provide broadly, a locking arrangement between the pump operating member, the housing and the nozzle valve whereby when the nozzle valve is supported in stationary position on the housing, it will be impossible to operate the pump or the liquid forcing means, and it will be impossible to operate or open the nozzle valve, or more broadly speaking, it will be impossible to operate the dispensing apparatus.

Still other objects of my invention are to provide a novel type of stationary support for the nozzle when not in use, whereby the same may be locked in position and whereby when so placed to be locked in position the pump control and liquid control are rendered automatically inoperable; to provide these and other objects of my invention which will be apparent from a perusal

of the following specification when taken in connection with the following drawings, wherein

Fig. 1 is a view partly in section of one form of my invention as applied to a remote control for a nozzle-operated mechanism for producing the desired sequence hereinbefore mentioned from the nozzle valve itself; 5

Figs. 2, 3 and 4 are section views showing the manner in which the nozzle valve and pump mechanism are operable; 10

Figs. 5, 6, 7 and 8 are section views showing the manner in which the cam mechanism is operable for carrying out the functions of Figs. 2 to 4 inclusive;

Fig. 9 is a perspective view of the nozzle valve 15 lever cam;

Fig. 10 is a perspective view of one form of my invention as applied to a pneumatic remote control between the nozzle valve lever and the pump or other liquid forcing means; 20

Fig. 11 is a sectional view of one form of my air valve for association with the apparatus shown in Fig. 10;

Fig. 12 is a view showing an adaptation of my invention providing an interlock between the 25 manually operable pump control member and a stationary support for the hose nozzle when not in use, and also a delivery valve if desired;

Fig. 13 is a fragmentary section taken along the line 13—13 of Fig. 12; 30

Fig. 14 is a partial sectional view of an adaptation of my invention to a manual control on the side of the housing on the pump switch; and

Fig. 15 is a view of the air cylinder co-operating with the air valve of Fig. 11. 35

Referring now to my invention in general, I have provided a liquid dispensing device of general application, but more particularly in mind for the dispensing of gasoline and other like liquids, wherein I desire to provide control mechanism between the pump or other liquid forcing means, which is adapted to draw the liquid from the usual storage tank and pass it through the dispensing hose under pressure and valve-controlled mechanism for controlling the flow of the fluid through the hose wherein a desired sequence of operation between the opening and closing of the valve and the liquid forcing means, such as the pump, is effected, so that at the initiation of the dispensing operation the usual hammering action will be prevented by opening the liquid controlling valve and operating the pump or other liquid forcing means either simultaneously or operating the liquid forcing means or pump slightly subsequently to the opening of the valve 40 45 50 55

and on the approach or conclusion of the dispensing operation to secure a maintained control of pressure on the liquid passing through the nozzle valve by maintaining the pump or liquid forcing means in operation until after the closing of the valve. This sequence of operation, i. e., the control of the pump, may be carried out either as a remote control, i. e., by controlling the pump or other liquid forcing means automatically from the operation of the nozzle valve, or by instrumentalities located adjacent the nozzle valve and carried thereby, but not necessarily an automatic operation, or by instrumentalities disposed on the housing or remote from the nozzle valve. The control mechanism itself may be of any desired nature such, for instance, as an electrical control mechanism for automatically interconnecting the nozzle valve and the liquid forcing means such as the pump, or alternatively, a pneumatic arrangement, or hydraulic arrangement, or a mechanical arrangement such as a Bowden wire, or its equivalent. In the present instance I have illustrated one embodiment of my invention as a pneumatic arrangement purely for the purpose of exemplification and not by way of limitation, and I have selected, for this purpose, the pneumatically controlled mechanism disclosed in the co-pending application of Clement P. Griffith, Serial No. 385,165, filed August 12, 1929, and in which present illustration I have modified certain features of the aforementioned Griffith application for the purpose of carrying out my desired sequence.

In my present invention I have also provided a new type of means providing a support for the hose when not in use, as for instance, when it is positioned on the housing after the dispensing operation, or when it is placed on the housing and locked in position for the night, wherein there is provided an automatic interlock for the pump or liquid forcing means, and also wherein instrumentalities are provided so that when the nozzle is stationarily positioned, as aforesaid, the pump or liquid forcing means is automatically locked in inoperative position, and wherein these same instrumentalities will prevent the operation of the nozzle valve lever and/or alternatively, if desired, the operation of the delivery valve, and also wherein these same instrumentalities prevent the positioning of the nozzle on said stationary support in any other position than the one which will bring about the automatic interlock to prevent flow of the liquid when the device is so positioned, and alternatively, when the nozzle is removed from its position, these instrumentalities will automatically unlock the pump or liquid forcing means so that it can be given a manual operation, if desired.

Referring now to the drawings in detail, in Fig. 10 I have shown the upper portion of the housing, shown more in detail in Griffith application Serial No. 385,165, to which reference may be had, for purposes of explaining more in detail, if desired, that the housing comprises an upstanding member 2 of preferably sheet metal construction, and embodies a liquid flow pipe 4 connected to a pump or other liquid forcing means, which pump preferably is mounted in the housing, or may be mounted outside of the housing, as shown in the aforesaid Griffith application. This pump, in turn, is connected to a reservoir or tank in the usual customary manner so that when the pump is in operation it will draw liquid from the tank, force it through the conduit 4 and through a delivery valve 6, if a delivery valve is desired.

At this point I wish to state that in the present type of apparatus these delivery valves are considered unnecessary since the nozzle valve control is deemed sufficient for governing the flow of liquid through the hose, however, it may be that in certain instances I desire to provide the delivery valve 6 in addition to the nozzle valve, or I may eliminate the nozzle valve and control the flow of liquid from the delivery valve 6. This delivery valve may be considered for generic purposes, as a valve controlling the flow of liquid through the hose, as an alternative to the nozzle valve, if desired.

Liquid from the pipe 4 passes through conduit 8 and thence through a usual meter, the dial 10 of which is illustrated in the drawings, and thence through conduit 12 through the usual sightglass 14, thence through the flexible hose 16 to the nozzle 18, thence through the nozzle valve 20 in a manner well known in the art. The details 15 of my preferred type of nozzle valve are shown in Fig. 1.

In the remote control type of device as shown in Figs. 1 to 11 and 15, the cover 18 is provided with a guard 22, which forms a sort of protective 25 housing for a manually operable nozzle valve operating member 24 in the form of a lever pivoted as at 26 to the body of the nozzle. This lever is adapted to co-operate with another lever 28 pivoted as at 30 to the nozzle. The end of lever 24 is formed to co-operate with lever 28. Lever 24 is adapted to be manually operated by means of the hand when gripping the nozzle, and this lever 24 serves to operate the nozzle valve 20 and also the lever 28 which remotely controls the 30 pump or other liquid controlling means in a manner about to be described.

The nozzle valve 20 is provided with the usual stem 32 and spring 34, which latter spring keeps the nozzle valve on its seat unless manually 40 opened. The end of the valve stem 32 passes outwardly through a usual packing 34' and lies opposite a screw 36 adjustably mounted on the lever 24. An aperture 38 in the guard permits the adjustment of screw 36. The screw 36 is for the purpose of controlling the opening of the valve 20 at various times in connection with the amount of movement of the lever 24 and consequently the movement of the pump-operating 45 lever 28.

The end of lever 24 is preferably bifurcated as at 40 and 42 to provide a seat for a cross pin 44 on which is mounted a roller having a portion 46 of large diameter and a portion 48 of smaller diameter. This roller is freely slidable longitudinally of the pin 44 and is adapted to co-operate with the cam lever 28 in the manner shown in Figs. 2 to 8 inclusive, to operate a plunger 50 for operating the pump or liquid forcing means. In the present case this plunger, as shown in Fig. 11, is a plunger of an air valve for controlling the flow of air from any desired source through certain pneumatic connections to the pump operating mechanism or other liquid forcing means, as hereinafter will be described.

Referring now to Fig. 1, it will be noted that the nozzle valve is closed and the power is off. It will be noted from the position of levers in Fig. 2, and in Fig. 5, which show corresponding 70 positions, that lever 24 has been raised up to a point wherein nozzle valve 20 is partially opened and the roller 46 at the end of the lever has not yet contacted lever 28 in such a manner that the power is turned on. When lever 24 is raised, a little further, there is presented a condition 75

as shown in Figs. 3 and 6 wherein the valve is open and the power has been turned on. Fig. 7 shows the initiation of the reverse motion, that is, when the nozzle valve is closing and Figs. 5 and 8 show a condition where the valve 20 has been closed but the power is still on. A further downward movement of valve lever 24 will shut off the power. This is accomplished by shifting the position of the contact roller 46 by 10 means of the cam surface 54.

By referring to Fig. 9 it will be clearly seen that as the lever 24 is shifted, the roller contacts with the cam surface 56, so that the roller runs up this surface, and then the roller contacts 15 with the cam surface 52, which moves the roller laterally on its pin onto the narrow lug 58 of the lever 28. This cam surface is so positioned that the valve is opened, but the lever is not pressed down. This is due, in part, to the smaller diameter of the roller 46. Since this smaller diameter roller rolls up the inclined surface 56, it positions the larger diameter roller 46 on the lug 58. It will be noted that the cam portion 56 is somewhat higher than the cam portion 58 of 20 the lever 28. This will accommodate the difference in diameters of the two rollers, and will permit the positioning of the larger roller 46 on the cam portion 58 as shown in Fig. 5 without causing the initial depression of lever 28 during the opening of the valve stem by the lever 24. As the lever 24 continues to move, the valve will open wider and wider and simultaneously therewith the roller 46 will move along the cam-shaped portion 58, thereby pressing the lever 35 about its pivot, and pushing the plunger 50 inwardly so as to actuate the pump or liquid forcing means. On the return movement, or as the lever 24 is reversely shifted by means of the spring 34, and as the lever 28 is shifted by means 40 of the spring in the air valve, as hereinafter referred to in Fig. 11, the roller 46 will move down the longer lever portion 58 as shown by dotted lines. As this lever portion 58 is longer than the corresponding lever portion 56, the lever 28 will be maintained in shifted position so as to keep the pump in operation after the nozzle valve stem 32 has been moved back to a 45 position such that the valve is fully closed.

As the roller 46 reaches the end of the cam-shaped portion 58, it will strike the inclined portion thereof (54) which will cause the rollers 46-48 to be shifted to the right so as to be opposite the upwardly inclined portion 56 of the lever 28 so that the next time the lever 24 is shifted, the sequence will begin again as heretofore described.

In order to operate the pump or other liquid forcing means automatically, I have provided a pneumatic motor 65, which is preferably under the control of the operator at the nozzle. As 50 shown in Fig. 15, the motor comprises a casting, the lower end of which is closed by the screw-threaded cap 66. Within the interior cylinder 67 is a piston 68 to the lower side of which is connected a plunger 69 movable vertically through the cylindrical guide 70 secured to the cap 66. A spring 71 surrounds the cylindrical guide 70 and the cylindrical guide is located between the top 55 of the cap 66 and the bottom of the piston 68.

The plunger 69 extends through an opening at the center of the cap 66 and its lower end rests upon the horizontal arm 72 which is provided with a collar, not shown, at its left-hand end, the latter being keyed to the lower end of the 60 rod 74. The rod 74 is guided through openings

in brackets 75-76, which are secured to the end of the wall of the housing 77, which encloses the delivery valve 6 and the operating mechanism thereof. The upper end of the rod 74 is connected by a pin and slot, as indicated at 78 (Fig. 5) to the crank arm 61 of the delivery valve 6; therefore, when the pneumatic motor is operated to depress the piston 68 against the action of the spring 71, the plunger 69 will actuate the bracket arm 72 and push down the rod 74 through the 10 guides 75 and 76, and thereby turn the crank arm 61 in an anti-clockwise direction to effect the opening of the valve 6. When air pressure on the piston 68 is relieved, the spring 71 restores the plunger 69 to its initial position and the 15 spring not shown simultaneously restores the rod 74 and the arm 72 to their initial positions, and recloses the valve 6. In order to permit free downward movement of the piston an air port 20 is provided at 79.

The cap 66 is shown in Fig. 15.

Air pressure may be conducted into the cylinder 67 through the connection at 80, as shown in Fig. 15. A small flexible pipe, preferably of metal such as copper, is led upwardly from the 25 connection 80 as shown, to the conduit 82, which is mounted by means of the bracket 83 on the vertical pipe 12. Also extending upwardly into the conduit 82 is a compressed air pipe 84, preferably of flexible metal such as copper. By 30 referring to Fig. 10 it will be seen that the pipe 84 is adapted to be connected to a compressed air supply of any desirable type. By means of a suitable air tube adaptor 90, the upper ends of the two metal pipes 81 and 84, and a flexible 35 hose 87, are mounted on and attached to the delivery hose 16 so as to move bodily therewith. For this purpose the flexible hose 87 may be secured to the delivery hose 16 by spirally wound tape or by means of clamps 88.

Air valve controlling mechanism 89 is connected by means of the air tube adaptor 90 to the flexible pipe 87 having the two air passageways 81 and 84 therethrough. The air valve mechanism 89 may be detachably secured to the valve 45 hose housing 18 as shown in Fig. 1. The details of the valve mechanism 89 are shown in Fig. 11. In this view the air tube adaptor is provided with two branches of flexible hose having the 50 passageways 81 and 84 leading respectively to the ports 95 and 94. These ports may be in the form of nipples 93 and 96, screw threaded into the body portion of the valve mechanism. The port 95 communicates with the passageway 97 and leads to oppositely disposed valve ports 98 and 55 99. Passageway 97 may be closed at 100 by means of a screw plug. The valve stem 101 has mounted thereon two valves 102 and 103. Between the nipple 96 and the valve 102 is a spring 104 which urges the valve 102 to closed position. The valves 102 and 103 are so related that when the port 98 is closed, port 99 is open. When the valve 103 closes the port 99, the valve 102 opens the port 98. When the valve 102 is closed, communication from the source of compressed air through pipe 84 to the pneumatic motor 65 is shut off.

When the valve 102 is closed, valve 103 is opened, and at this time the pneumatic motor 65 is connected through the pipe 81 to the passageway 97 and the port 99 to the chamber 105 and exhaust port 106, thereby relieving the air pressure on top of the piston 68 and permitting the spring 71 to return the piston to its initial position as shown in Fig. 15.

As shown in Fig. 11, the plunger 50 extends 75

through a bearing 108 which is threew-threaded into one end of the cylinder 109. At the inner end of the plunger 50, is a piston 110 movably along the cylinder 109. An inner end of the plunger 50 is provided with a recess 111 fitting over the valve stem 101. The piston 110 presses against the spring 112 when the plunger 50 is moved inwardly. The inward movement of the plunger causes the piston 110 to act as a valve to cut off the exhaust port 106 from the chamber 105, and the port 99. This is followed by the closure of the valve 103 and the opening of the valve 102 when sufficient force is exerted on spring 112 to counteract the spring 104. It is desirable to close the port 106 before the valve 102 is opened so that compressed air cannot escape from the supply passageway 84 through the exhaust port during the interval when the valves 102 and 103 are both open.

20 By referring to Fig. 1 it will be seen that when the nozzle is grasped in the operator's hand with his palm over the valve, his fingers may be used to move the lever 24 inwardly away from the guard and this operation will open the valve 20. 25 Before the valve 20 is open, however, the roller end of the lever will ride along the cam faces of the lever 28 in the manner hereinbefore described.

As shown clearly in Fig. 15, an extension 141 is carried by the bracket arm 72 and to this extension 141 is pivoted at 142 a bar 143, which has sliding connection through a diametrical opening in the shaft 144. This shaft is mounted in the bearings 145 of the switch box 146. Mounted on the inner end of the shaft 144 are suitable means for engaging the opposite surfaces of the vacuum tube 148 preferably of glass and containing within the same quantity of mercury for engaging the terminals 150 and 151, which project into the last vacuum tube 148, as illustrated in Fig. 14. The terminals of the vacuum tube are suitably connected to a source of current, as illustrated in the prior Griffith application Serial No. 385,165, whereby on rocking of the mercury tube, the switch will be made or broken to start and stop the electric motor operatively connected to the pump or to operate any type of valve or other mechanism for controlling the liquid forcing means of any desired type.

It is usually understood that when the operating lever 24 of the nozzle valve is shifted, exhaust port 106, as shown in Fig. 11, will be first closed and this will be followed by the closing of the valve 103 and the opening of the valve 102. The air pressure supply will then pass into pipe 84 and thence through the passageway of the flexible hose 87. This air pressure will then pass through the port 98 and passageway 97 into the passageway 81, and the top of the cylinder 67. The piston 68 will move downwardly against the action of the spring 71 while the air below the piston 68 will be exhausted through port 79. This will cause the plunger 69 to be moved downwardly to pull rod 74 downwardly, thereby operating the crank 61 in an anti-clockwise direction to cause the delivery valve 6 to open, to afford communication between the supply pipe 4 and the pipe 8 leading to the dispensing hose 16. At the same time the delivery valve 6 is opened, the mercury switch will be tilted to horizontal position from its inclined position. The mercury in the closed vacuum tube 148 will thereupon connect the terminals 150 and 151 to start the motor, to continue operating as long as the terminals are connected by the mercury 139. When the motor is operated, pump 16 will operate to pump

gasoline through the suction pipe and supply it to the pipe 4, delivery valve 6, through pipe 8 to the delivery hose 16 in a manner well known in the art.

It is understood that the pump is provided with the usual by-pass, all as shown in the prior mentioned Griffith application. 5

When the operator releases the lever 24, the spring 34 closes the nozzle valve 20 and returns the lever 24 to its initial position. At the same time the plunger 50 is returned to its initial position by the springs 104 and 112 and the lever 28 will thus be returned to its former position. When the operator releases the lever 24 and therefore the lever 28, the spring 104 is free to act to close the valve 102. This will also effect the opening of the valve 103 when the spring 112 in turn acts on piston 110 to uncover the exhaust port 106 so that a chamber 105 will be connected to the atmosphere. This will result in the cylinder 67 being connected to atmosphere above the piston 68 through pipe 81, passageway 97 and port 99, chamber 105 to exhaust port 106. A spring, not shown, in the valve 6, will then close the valve and act through rock-shaft 52 and 25 the crank of said valve to lift rod 74 back to its initial position. This will also lift the extension 141 to its initial position and swing the rod 143 to its position, whereupon the mercury switch will be tilted, thereby disconnecting the terminals 150 and 151 and cutting off the electrical current supply to the motor causing the pump 16 to stop.

In Figs. 12 and 14 I have disclosed a modification of my invention wherein I provide a manually operable control means, preferably positioned on the side of the housing for operating the pump, and a liquid delivery valve in the desired sequence above set forth. In this construction the housing 160 is provided with a preferably 40 mushroom-shaped manually operable head 162 originally mounted on a shaft 164 to which is affixed a crank 166, having a rod 168 connected thereto. This rod passes downwardly and it is adapted to operate a vertically slidable rod 170 45 having its lower end pivotally connected as at 172 to a lever 174 in turn pivoted as at 176 in the switch-housing. The inner end of this lever 174 is provided with a bifurcated head carrying a roller, the same type as is illustrated in Figs. 1-50 to 9 inclusive, and in turn co-operates with a lever 178 having its inner end configured exactly like the lever 28 of Fig. 9. This lever 178 is pivoted as at 180 and suitable spring 182 is provided to return the lever to desired normal position. 55 The upper portion of lever 178 is provided with a mercury switch 148 as hereinbefore described.

In this device, the rod 170 is provided with a slot and pin connection 182 with a link 184 in turn connected with a crank arm 186 connected 60 to a shaft 188 in which is disposed a delivery valve of any desired construction, but preferably as shown in the prior mentioned Griffith application Serial No. 385,165. By reason of this construction, when the head 162 is turned, the rod 168 is operated to shift the sliding rod 170 vertically whereby to cause movement of the link 184 and movement of lever 174 to secure the same sequence of operation as hereinbefore described-70 in connection with Fig. 1.

In connection with the device for manually controlling a delivery valve and for operating the pump switch, I provide the housing 160 with a stationary support adapted to receive the nozzle 75

when not in use. In this connection the wall 160 of the housing is provided with a vertically disposed recess 190 to receive the flexible portion of the nozzle and I preferably provide a depending 5 lip portion 192 which is adapted to overhang the end of the nozzle when inserted in its vertical seat. In addition the lower end of the housing stops at the point 194 to co-operate with a lower rim portion 196 of a lower portion of the housing to provide 10 an opening of sufficient height and width to accommodate the nozzle proper, and so that the guard of the nozzle and the nozzle lever 24' will lie within the exterior planes of the housing, whereas the portion 18' of the nozzle will lie outside 15 of the exterior planes of the housing. In addition I preferably provide the housing with two outstanding ears 192 which have downwardly slanting surfaces 195 and which are provided with registering apertures 197 through which a 20 padlock 198 may be passed when the nozzle is in its seated position. In addition I provide within the housing and opposite the opening a pivotally mounted interlocking device comprising an abutment 199 suitably weighted as at 200 and 25 pivotally mounted as at 202. This abutment is provided with an upstanding arcuate toe 204 which in one position is adapted to underlie the pin 206 which interconnects the vertical slide rod 170 and the link 184. The operation is such 30 that when the nozzle is placed in position on its seat the nozzle guard will force the abutment 198 inwardly and upwardly and thereby cause the rigidly mounted arcuate toe 204 to ride under the pin 206 interconnecting the rod 170 and the link 35 184. When in this position it will be impossible to operate the head 162 to either open the valve or operate the pump switch. When the nozzle lever is withdrawn the weight 200 of the abutment will swing down to such a position as to substantially 40 close the opening in the housing and the toe 204 will shift to a position from under the pin 206, thereby permitting the manual operation of the control member 162 to both open the delivery valve and to operate the switch for the pump, 45 or its equivalent. It will be noted that when the nozzle is in position shown in Fig. 12, and the padlock passed therethrough, the nozzle will be locked through the housing; the pump control member and the valve control member 162 will be 50 locked in inoperative position and it will be impossible to reach the nozzle valve delivery valve to operate the same, due to the fact that it lies within the exterior planes of the housing and is shielded from access by means of the nozzle itself. It will also be appreciated that by reason 55 of the sloping sides 194 of the two ears 192, the nozzles cannot be hung sidewise on the ears, but can be only seated in their proper place in such position as is indicated in the drawings, whereby 60 means is provided for automatically locking the pump operating means or valve opening means from operation when the nozzle is placed upon its support.

It must be obvious by referring to Fig. 1 of the drawings that in lieu of using an air valve 89 and its co-operating mechanism shown in Fig. 15 of the drawings, that I am enabled to operate my pump and nozzle valve in the desired sequence in a remote controlled manner by substituting a solenoid for the device 89 and having proper electrical connections for causing the operation of the pump switch therefrom in the manner set forth in a co-pending application filed by Junius F. Cook and James Ballard Moore, to which reference is made for a fuller disclosure of said in-

vention, or I may utilize any type of Bowden wire device such as shown in the patents to Stedwell or Hawkhurst for causing the operation of the pump switch by the operation of a plunger 50 shown in my present drawings, or alternatively, I may cause the plunger 50 to operate one end of a sylphon construction containing oil, the interior of which sylphon is connected with a flexible hose likewise full of liquid and extending along the flexible hose 16 and likewise connecting at the other end to a sylphon which, in turn, is adapted by its movement to operate a lever mechanism 143 of the pump switch, as shown herein, whereby upon operation of the plunger 50, operating on the sylphon system, the liquid column will cause the operation of the lever 143 to operate the mercury switch in accordance with my disclosed sequence of operation in connection with the nozzle valve mechanism. 10 15

Having thus described my invention, what I claim as new and desire to secure by Letters Patent is:

1. In a liquid dispensing system, a liquid delivery line terminating in a flexible hose, controllable means for supplying liquid through said line and hose, a valve controlling discharge through the hose, and operating means for starting the liquid supplying means and opening the valve simultaneously and for closing said valve and for stopping said means after the valve has been closed. 20 25

2. In a liquid dispensing system, a liquid delivery line terminating in a flexible hose, controllable means for supplying liquid through said line, and operating means for opening the valve 30 and then starting the liquid supplying means and for then closing said valve and stopping said means after the valve has been closed. 35

3. In a liquid dispensing system, a liquid dispensing hose having a nozzle valve, a flexible connection extending from the nozzle valve back along the hose, flow regulating means actuated by said flexible connection, a flow meter in service relation to the hose, and instrumentalities associated with said flexible connection and said nozzle valve, arranged to prevent pressure on said nozzle valve, prior to its opening and to maintain pressure on said nozzle valve after its closing. 40 45

4. In a liquid dispensing system, a liquid delivery line terminating in a flexible hose, controllable means for supplying liquid through said line and hose, a nozzle valve controlling discharge from the hose, and operating means for starting the liquid supplying means and for opening the nozzle valve simultaneously with the operation 50 of said means, and for closing said nozzle valve and stopping said means after the nozzle valve has been closed. 55

5. In a liquid dispensing system, a liquid delivery line terminating in a flexible hose, controllable means for supplying liquid through said line and hose, a nozzle valve controlling discharge through the hose, and operating means for opening said nozzle valve and then starting the liquid supplying means and then for closing the nozzle 60 valve and then stopping said means after the nozzle has been closed. 65

6. In a liquid dispensing system, a delivery line, a hose connected therewith, a delivery controlling valve in said delivery line, an electric control 70 switch, and operating means for opening the delivery valve and closing the switch simultaneously and for opening the switch after the delivery valve is closed.

7. In a liquid dispensing system, the combina- 75

tion of a hose terminating in a nozzle having a valve, a manually operable means on said nozzle for opening said valve, means providing an adjustment for determining the time of opening of said valve with respect to the movement of the opening of said manually operable means, a shiftable device mounted on said nozzle and operated by the movement of said manually operable means, a pump, means for actuating said pump including a control device operated by said shiftable device, and means operatively interconnecting the manually operable means and the shifting device, whereby the pump will be maintained in operation after the closing of said valve and whereby the pump will be started simultaneously with or subsequently to the opening of said valve.

8. In a liquid dispensing device, in combination with a hose provided with a nozzle, a valve in said nozzle, a lever mounted in said nozzle and adapted to be manually operable to open said valve, said lever having at its extremity a roller having diametral portions of different dimensions, a second lever mounted on said nozzle and arranged in the path of movement of said first mentioned lever, a shiftable member adapted to be actuated by movement of said second lever, remote control connections from said shiftable member, a pump, operating means for said pump including a switch connected to said remote control connections, said second lever having two portions, one of which is shorter than the other, said portions having cam-shaped surfaces whereby upon actuation of said first-mentioned lever, the smaller diameter of said roller will be caused to ride upon said shorter portion and move laterally thereon onto the longer portion without substantially shifting said second mentioned lever and will thereafter ride along said longer portion to depress said lever and upon return movement of said first mentioned lever, said roller

portion of larger diameter will reversely roll on said longer portion and maintain said second lever in depressed position until after the return of said first lever to valve-closed position, the cam surface of said longer portion serving to return said roller member to its original position.

9. In a liquid dispensing system, the combination of a hose having a nozzle, a switch, a pump and a pump switch, a lever for operating the valve to cause it to open, a second lever adapted to actuate remote control connections passing along the hose to the pump switch, and connections between said levers including cam surfaces on one of said levers and an operating member carried on the other of said levers whereby upon the actuation of one of said levers said valve will be opened and said remote control connections will be operated, whereby said pump will not be operated until the valve opens and whereby upon return movement of said lever said pump will be maintained in operation after the closing of said valve.

10. In a liquid dispensing device, the combination of an upstanding housing, a meter in said housing, a liquid dispensing line, a pump for passing liquid through said line and through said meter, said line terminating in a hose outside of said housing, said hose being provided with a nozzle, a valve for controlling the flow of liquid through said line, a member projecting from said housing for opening and closing said valve, a connection from said member to said pump switch including instrumentalities whereby upon the opening of said valve, said pump switch will not be operated until at least the opening of said valve and whereby upon the closing of said valve said pump switch will be maintained in pump operating position until after the closing of said valve.

CARL E. CARLSON. 40.
